UNITED STATES PATENT OFFICE.

REGINALD HUGH SPENCER BACON AND JOHN HERBERT MANSELL, OF COVENTRY, ENGLAND, ASSIGNEES TO THE COVENTRY ORDNANCE WORKS, LIMITED, OF COVENTRY, ENGLAND.

FUSE.

1,161,147.

Specification of Letters Patent. Patented Nov. 23, 1915.

Application filed March 23, 1915. Serial No. 16,528.

To all whom it may concern:

Be it known that we, REGINALD HUGH SPENCER BACON and JOHN HERBERT MANSELL, subjects of the King of Great Britain, both residing at The Coventry Ordnance Works, Coventry, in the county of Warwick, England, have invented new and useful Improvements in Fuses, of which the following is a specification.

10 This invention relates to improvements in fuses for high explosive shells its object being to provide a fuse which shall produce a powerful detonation so as to detonate with certainty the charge of the shell and shall 15 also be safe to handle.

Our invention is illustrated by the accompanying drawing which is a longitudinal section through a fuse.

20 *a* is the body of the fuse containing time rings *b* and a percussion pellet *c* of ordinary construction. Into the body screws a strong steel gaine *d* into which gaine is screwed a diaphragm *e*. In front of this is a charge *f* of high explosive such as trinitrophenylmethylnitramin or tetryl as it is more conveniently called, in the middle of which are pellets *g* of powder. In front of this is a wad *h* which is kept in place by the screw plug *i* through which is formed a passage to enable 25 the flash from the percussion or time arrangements to reach the pellets *g*. In front of this again is another plug *j* containing a centrifugal safety bolt *k* in front of which is a copper cup *l* which normally closes the passage. Behind the diaphragm *e* is a larger 30 charge of high explosive such as tetryl, the front portion being formed of loose explosive *m* while the rear portion is composed of compressed explosive *n*, the two being 35 separated by a wad *o* and held in place by a plug *p*.

When the shell has been fired centrifugal

action causes the bolt *k* to move outward so that when the flash from either the time or percussion arrangement reaches the copper 45 cup *l* the latter is forced into the space previously occupied by the bolt and the flash then passes down the passage in the plug *i* and ignites the pellets *g* which explode the small charge *f*; the explosion of this is sufficient to perforate the diaphragm *e* and to detonate the larger charge of high explosive 50 in the rear of the gaine, the detonation of this in turn being sufficient to explode the charge of the shell. 55

What we claim is:—

1. In a shell fuse the combination of a gaine, a solid, transverse diaphragm therein, a charge of high explosive in front of the diaphragm, a larger charge of high explosive 60 in rear of the diaphragm and means for exploding the first mentioned charge.

2. In a shell fuse the combination of a gaine, a solid, transverse diaphragm therein, a charge of high explosive in front of the 65 diaphragm, a charge of high explosive in rear of the diaphragm such charge being composed of a front portion of loose explosive and a rear portion of compressed explosive, and means for exploding the first men- 70 tioned charge.

3. In a shell fuse the combination of a gaine, a solid, transverse diaphragm therein, a charge of high explosive in front of the diaphragm, a powder charge in the interior 75 of such charge, a charge of high explosive in rear of the diaphragm and means for exploding the powder.

REGINALD HUGH SPENCER BACON.
JOHN HERBERT MANSELL.
